US00D896384S

(12) **United States Design Patent** (10) **Patent No.:** **US D896,384 S**
(45) **Date of Patent:** **** Sep. 15, 2020**

(54) **SPINAL FUSION CAGE**

(71) Applicant: **GetSet Surgical SA**, Epalinges (CH)

(72) Inventors: **John Kapitan**, Leicester, NC (US); **Ole Stoklund**, Lausanne (CH); **Lawrence Binder**, Miami, FL (US)

(73) Assignee: **GetSet Surgical SA**, Epalinges (CH)

(**) Term: **15 Years**

(21) Appl. No.: **29/694,205**

(22) Filed: **Jun. 7, 2019**

(51) **LOC (12) Cl. 24-03**

(52) **U.S. Cl.**

USPC **D24/155**

(57) **CLAIM**

The ornamental design for a spinal fusion cage, as shown and described.

DESCRIPTION

FIG. 1 is a front, left, and top isometric view of a spinal fusion cage.

FIG. 2 is a rear, right, and top isometric view of the spinal fusion cage.

FIG. 3 is a left elevation view of the spinal fusion cage.

FIG. 4 is a right elevation view of the spinal fusion cage.

FIG. 5 is a rear elevation view of the spinal fusion cage.

FIG. 6 is a front elevation view of the spinal fusion cage.

FIG. 7 is a top plan view of the spinal fusion cage; and,

FIG. 8 is a bottom plan view of the spinal fusion cage.

1 Claim, 7 Drawing Sheets
